DOUBLE ACTING PUMP

Filed Sept. 24, 1928

INVENTOR:
John S. Hunter,
BY Fred J. Davis

ATTORNEY.

UNITED STATES PATENT OFFICE

JOHN S. HUNTER, OF COALINGA, CALIFORNIA

DOUBLE-ACTING PUMP

Application filed September 24, 1928. Serial No. 307,946.

- This invention relates to well pumps, and more particularly to double acting pumps adapted for operation in a working barrel or in a pump tubing.
- 5 It is an object of this invention to provide a double acting pump adaptable for pumping oil from a well, although the invention may be used to pump water or any other liquid desired, and its use should not be limited thereto by the following description, or by the accompanying claims.
- 10 It is a further object of this invention to provide a pump which utilizes both the down stroke and the up stroke of the sucker-rods for pumping purposes, thus greatly increasing the pumping efficiency of the mechanism over previously manufactured single action pumps which utilize the movement of the sucker rods in one direction only.
- 15 20 It is a still further object of this invention to provide a double acting pump comprising outer and inner pump barrels in fixed relation, and a piston connected to the lower end of the sucker-rods, or other pumping means in the well, and adapted to be reciprocated in the inner pump barrel, and valve means for controlling the flow of liquid in the pump.
- 25 Other objects and advantages of my invention will be made evident hereinafter.
- 30 Referring in detail to the drawings,—
- Fig. 1 illustrates a sectional longitudinal view of the upper end of my invention.
- Fig. 2 illustrates a sectional longitudinal view of the lower end of my invention.
- 35 Fig. 3 is a cross-sectional view taken on the line 3—3 of Fig. 1.
- Fig. 4 is a cross-sectional view taken on the line 4—4 of Fig. 1.
- 40 Fig. 5 is a cross-sectional view taken on the line 5—5 of Fig. 1.
- Fig. 6 is a cross-sectional view taken on the line 6—6 of Fig. 1.
- 45 Fig. 7 is a cross-sectional view taken on the line 7—7 of Fig. 2.
- This invention comprises an outer pump barrel 12 having fixed therein an inner pump barrel 13 through which a piston means 14 is adapted to be reciprocated by means of sucker-rods 15, as illustrated in Figs. 1 and
2. The outer barrel 12 has external threads 16 at its upper end, said threads being adapted to be received by internal threads 17 on a well-tubing 18, thus retaining the double action pump construction of this invention 55 in fixed relation to the well-tubing. The outer barrel 12 comprises a lower tubing member 19 having internal threads 20 at its upper end, which threadedly receive external threads 21 of an upper tubing member 22. The wall of the upper tubing member 22 is slightly thicker than the wall of the lower tubing member 19, and a shoulder 23 is formed on the inside surface thereof. 60
- A short collar 24 makes a tight sliding fit 65 around the inner pump barrel 13 and is provided with a shoulder 25, which engages the shoulder 23. The collar 24 is provided with openings 26, as shown in Figs. 1 and 4. It is desirable, though not necessary, that the 70 collar 24 also have a tight sliding fit with the inside of the outer pump barrel 12, so as to maintain a more rigid relationship between the inner and the outer pump barrels. The upper member 22, above the shoulder 23, 75 thus forms a continuation of the well-tubing 18 to the lower end of which the pump is attached and defines a fluid discharge cavity or passage 61 which communicates directly with the bore of the well-tubing. 80
- Forming a tight sliding fit with the inside surface of the inner pump barrel 13 is a sleeve member 27, comprising a sleeve portion 28 and a head portion 29 formed integrally therewith. The sleeve portion 28 is 85 provided with openings 30, as shown in Figs. 1 and 4, and openings 31, as illustrated in Figs. 1 and 5, and is adapted to engage a shoulder 32 formed on the inner pump barrel 13. 90
- Connecting a cavity 33 of the inner pump barrel 13 and the space around the outer pump barrel are ducts 34 as shown in Figs. 1 and 5, and are in alignment with the openings 31 when the sleeve member 27 is in its lowermost position so that the sleeve portion 28 engages the shoulder 32. In the sleeve portion 28 is a bearing 35 through which the sucker-rod 15 passes, and which prevents whipping in the sucker-rod to a large degree 100

when the pump is in operation, and also maintains the sucker-rod in axial alignment through the pump mechanism. The construction of the bearing 35 is clearly illustrated in Figs. 1 and 6.

6 The limit of upward movement of the sleeve member 27 is regulated by control means comprising a set screw 36 threadedly received in the outer and inner pump barrels and extending into a longitudinal slot 37 in 10 the sleeve portion 28, said set screw 36 also preventing the rotation of the sleeve member 27. The action of this control means is most important, because if the sleeve member 27 were allowed to rotate, however little, such 15 rotation would throw the openings 31 out of alignment with the ducts 34, which would be fatal to the successful operation of the pump, as will be readily seen from the description 20 of the operation of the pump given below.

In the head portion 29 of the sleeve member 27 is a stuffing box 40 closed by a bolt 42 through which the sucker-rod 15 passes, preventing oil from leaking from the well-tubing back into the pump.

25 The upper surface of the collar 24 contacts a compression spring 38 of nearly the same diameter as the diameter of the collar 24, said compression spring 38 being prevented from 30 moving upward beyond its limits of compression by a bearing 39 which it engages, said bearing 39 being adapted to be rigidly retained by the outer pump barrel and to keep the sucker-rod 15 in alignment through the 35 pump mechanism. The bearing 39 is similar in construction to the bearing 35 in the sleeve member 27.

At the lower end of the inner pump barrel 13 is a flange 45 associated with the inner 40 pump barrel 13 so as to engage the outer pump barrel and to hold the inner and outer pump barrels in fixed relationship. Adjacent to the flange 45 in the inner pump barrel 13, are orifices 46. The piston means 14, as shown 45 in Fig. 2, is associated with the lower end of the sucker-rod 15, and comprises a plurality of piston cups 47, formed of leather or any other suitable material. The piston cups 47 are aligned on the sucker-rod 15 and are 50 spaced by washers 48. In the assembling of such a piston for a double action pump, some of the piston cups are inverted and some placed upright. I have illustrated this assemblage in Fig. 2, showing the upper piston 55 cups in an upright position on the sucker-rod 15, and separated from them by a spacer 49. I have shown the lower piston cups in an inverted position. The piston cups 47 are held rigidly on the sucker-rod 15 between a shoulder 50 formed integrally on said sucker-rod which contacts the uppermost piston cup 47, and a nut 51 threadedly received on the lowermost end of the sucker-rod which contacts the lowermost piston cup 47. The piston 60 means 14, when assembled in the manner de-

scribed, will permit a double action stroke with practically no leakage. However, any suitable piston means may be substituted for the particular means described above without departing from the spirit of the invention.

70 Internal threads 54 formed on the lower end of the lower tubing member 19 of the outer pump barrel 12, threadedly receive a downwardly closing valve means 55, comprising 75 a valve seat 56, a valve ball 57, and a cage 58 to confine said valve ball 57. This downwardly closing valve means 55 is of a standard and well known construction and is commonly referred to as a "standing valve" in 80 the trade. I shall hereinafter refer to said downwardly closing valve means 55 as standing valve 55. If the pump is to be used in oil wells, a section of screened pipe may be 85 threadedly attached to the lower end of the standing valve, although I have not shown it in the drawings.

It is necessary for the successful operation 90 of the pump that the liquid in the well strikes a level on the pump higher than the ducts 95 34, as liquid must pass into the pump through these ducts as well as through the standing valve 55. When the piston means 14 is in its downward position, as shown in Fig. 2, the weight of the sleeve member 27 will be sufficient to force the sleeve member into engagement with the shoulder 32 on the inner pump barrel 13, thus aligning the openings 31 and the ducts 34, and liquid will flow through these passageways into the inner pump barrel, and will fill it up behind the piston 14.

100 As the upstroke of the piston begins, the piston will exert considerable pressure on the liquid in the inner pump barrel 13. Although some of the liquid in the inner pump barrel 105 will be forced out of the pump through the passageways formed by the openings 31 and the ducts 34, the pressure on the liquid will not be entirely relieved and said liquid will exert a pressure on the lower surface of the 110 head 29 of the sleeve member 27, forcing the sleeve member 27 upwardly. As soon as the sleeve member 27 begins to travel upwardly, the openings 31 will be thrown further and further out of alignment with the ducts 34, until finally the openings 31 will be completely closed by the inner pump barrel 13, and when such occurs the pressure exerted by the piston 14 on the column of liquid behind, it will be approximately equal to the 115 pressure exerted by the liquid on the head member 29. The sleeve member 27 will continue to travel upwardly until the end of the slot 37 in the sleeve portion 28 engages the set screw 36, which engagement will stop the 120 upward movement of the sleeve member 27. When the sleeve member 27 attains its uppermost position, as shown by the dotted lines 125 60 of Fig. 1, the openings 30 will communicate with the cavity 61 in the upper portion 22 130

of the outer pump barrel 12, and most of the liquid in the inner pump barrel 13 will be forced therethrough by the piston 14.

When the piston 14 begins its upward stroke, the standing valve 55 is sucked open and liquid is sucked up into the inner pump barrel 13 by the upward motion of the piston 14 through the standing valve. Part of the liquid in the inner pump barrel 13 is forced by its own weight through the orifices 46 into the cavity 62 formed between the inner and outer pump barrels.

As the piston 14 begins its downward stroke, the weight of the column of liquid in the outer pump barrel 12 above the head 29 forces the sleeve member 27 downwardly, as there is no upward pressure of the piston opposing it, until the sleeve portion 28 once again engages the shoulder 32 on the inner pump barrel 13, thus aligning the openings 31 and the ducts 34 and closing the openings 30 so that the liquid above the sleeve member 27 cannot flow back into the inner pump barrel 13. At the same time the downward pressure of the piston 14 on the column of liquid ahead of it in the inner pump barrel 13, forces the standing valve 55 closed, and then forces the liquid through the orifices 46 into the cavity 62. Thus as the piston 14 moves downwardly it forces the liquid ahead of it through the orifices 46 and sucks liquid behind it through the passageways formed by the openings 31 and the ducts 34. The portion of the inner pump barrel 13 behind the piston 14 is then filling with liquid while the liquid ahead of the piston is being forced into the cavity 62.

The piston 14 exerts considerable pressure on the column of liquid in the cavity 62, which in turn exerts a pressure on the collar 24. When the upward force exerted by the column of liquid in the cavity 62 exceeds the combined downward forces of the compression spring 38 bearing against the collar 24, and the collar 24, the collar will move upwardly against the action of the compression spring, until the openings 26 communicate with the cavity 61 in the upper portion 22 of the outer pump barrel 12. At this time the liquid in the cavity 62 will flow into the cavity 61 and will thus relieve the pressure on the collar which will stop its upward movement. When the piston 14 comes to the end of its downward stroke and once more starts upwardly, the pressure of the compression spring 38 on the collar 24 will no longer be opposed by an upward pressure in the cavity 62, and the collar 24 will be forced downwardly until the shoulder 25 thereon engages the shoulder 23 formed on the upper portion 22 of the outer pump barrel 12, thus preventing the liquid in the cavity 61 from flowing back into the cavity 62.

From the foregoing description it is apparent that I have provided a double action

well pump that employs both the downstroke and the upstroke to pump liquid in a working barrel or pump tubing.

I claim as my invention:

1. In a double acting pump, the combination of: an outer barrel adapted for attachment to a well-tubing and provided at its lower end with downwardly closing valve means; an inner barrel fixed within said outer barrel, and communicating with said outer barrel by orifices at its lower end, said outer barrel being extended above said inner barrel to form a fluid delivery passage for delivering pumped fluid to said well-tubing; downwardly closing valve means comprising a collar slidably fitting on said inner barrel and adapted to control communication between a space formed by said inner and outer barrels and said fluid delivery passage; downwardly closing valve means comprising a sleeve member slidably fitting in said inner barrel and adapted to control communication between the interior of said inner barrel and said fluid delivery passage and also to control communication between the interior of said inner barrel and the space outside the outer barrel by means of a duct; and piston means adapted to be reciprocated within said inner barrel.

2. In a double acting pump, the combination of: an outer barrel adapted for attachment to a well-tubing and provided at its lower end with downwardly closing valve means; an inner barrel fixed within said outer barrel, and communicating with said outer barrel by orifices at its lower end, said outer barrel being extended above said inner barrel to form a fluid delivery passage for delivering pumped fluid to said well-tubing; downwardly closing valve means comprising a collar slidably fitting on said inner barrel and adapted to control communication between a space formed by said inner and outer barrels and said fluid delivery passage; downwardly closing valve means comprising a sleeve member slidably fitting in said inner barrel and adapted to control communication between the interior of said inner barrel and said fluid delivery passage, and also adapted to control communication between the interior of said inner barrel and the space outside the outer barrel by means of a duct; spring means rigidly associated with said outer barrel and adapted to engage said slidably fitting collar; and piston means adapted to be reciprocated within said inner barrel.

3. In a double acting pump, the combination of: an outer barrel adapted for attachment to a well tubing and provided at its lower end with a downwardly closing valve means; an inner barrel fixed within said outer barrel and communicating with said outer barrel at its lower end, said outer barrel being extended above said inner barrel to form a fluid delivery passage for delivering pumped

fluid to said well-tubing; downwardly closing valve means adapted to control communication between a space formed by said inner and outer barrels and said fluid delivery passage; 5 downwardly closing valve means comprising a sleeve member slidably fitting in said inner barrel and adapted to control communication between the interior of said inner barrel and said fluid delivery passage, and also adapted 10 to control communication between the interior of said inner barrel and the space outside the outer barrel by means of a duct; means for controlling the movement of said sleeve member; and piston means adapted to be reciprocated within said inner barrel.

15 4. In a double acting pump, the combination of: an outer barrel adapted for attachment to a well tubing and provided at its lower end with downwardly closing valve means; 20 an inner barrel fixed within said outer barrel, and communicating with said outer barrel by orifices at its lower end, said outer barrel being extended above said inner barrel to form a fluid delivery passage for delivering pumped 25 fluid to said well-tubing; downwardly closing valve means adapted to control communication between a space formed by said inner and outer barrels and said fluid delivery passage; downwardly closing valve means comprising 30 a sleeve member slidably fitting in said inner barrel and adapted to control communication between the interior of said inner barrel and said fluid delivery passage, said sleeve member cooperating with a duct adapted to communicate between the interior of said inner 35 barrel and the space outside said outer barrel; means for controlling the movement of said sleeve member; piston means adapted to be reciprocated within said inner barrel; and bearing means carried by said sleeve member 40 adapted to guide a means for reciprocating said piston means.

45 5. A combination as claimed in claim 2 in which means is provided for centralizing the piston reciprocating means.

45 6. A combination as claimed in claim 2 in which means is provided for controlling the movement of said sleeve member.

50 7. A combination as claimed in claim 2 in which means is provided for controlling the movement of said sleeve member and wherein the piston reciprocating means is centralized.

55 8. A combination as described in claim 4 in which means is provided for centralizing the piston reciprocating means.

In testimony whereof, I have hereunto set my hand at Los Angeles, California, this 11th day of September, 1928.

JOHN S. HUNTER.
